UNITED STATES PATENT OFFICE.

WILLIAM E. WALSH, OF NEW HAVEN, CONNECTICUT, ASSIGNOR OF ONE-THIRD TO CLAYTON S. REYNOLDS AND ONE-THIRD TO DANIEL MALONEY, BOTH OF NEW HAVEN, CONNECTICUT.

GRAPEFRUIT CORER.

Application filed April 7, 1927. Serial No. 181,678.

This invention relates to improvement in grapefruit corers, that is, devices for removing the cores from the halves of grapefruit, the object being to produce a device for this purpose which is easily operated and which completely cuts away the core, and the invention consists in the construction as hereinafter described and particularly recited in the claims.

10 In the accompanying drawings:

Fig. 1 is a side view of a grapefruit corer constructed in accordance with my invention;

15 Fig. 2 is an underside view of the same; Fig. 3 is a side view at right angles to Fig. 1; and

Fig. 4 is a sectional view on the line 4—4 of Fig. 1, showing by broken lines the cutter-ring in its cutting position.

20 In carrying out my invention, I employ a tubular cutter 5 provided at its lower end with a cutting-edge 6. Secured to this cutter is a handle-shank 7 provided at its upper end with a hand-grip 8. The handle-shank 7 is formed from sheet-metal and provided on opposite sides with slots 9 through which a pin 10 extends, and fixed to opposite ends of this pin, outside the shank, are finger-pieces 11. Pivots mounted in the 25 cutter 5 and substantially corresponding in diameter thereto is a cutter-ring 12 having cutting-edges 13 at the top and bottom, and one side of this ring is connected by a link 14 with the pin 10. Preferably, the edges 30 of the upper portion of the shank will be turned in to form a housing for a spring 16, the tendency of which is to force the link 14 downward so as to hold the ring 12 in a horizontal position.

35 In use, the cutter is placed around the core in half a grapefruit and pressed inward to the desired extent; then the finger-pieces 11 are drawn upward, so as to swing the cutter-ring 12 to a vertical position and, in so moving, the core is cut halfway through. The device is then rotated and, in rotating, the remaining portion of the core is severed. During the cutting operation, the cutter-ring 40 may be oscillated so that both of the cutting-edges are brought into action. After the core 45 is completely severed, the device is removed

and carries with it the core, which, when the finger-pieces are released, will drop out of the cutter.

I thus provide, in a very simple way, an 55 effective device for removing the cores of grapefruit, making a clean cut and completely removing the core.

I claim:

1. A grapefruit corer, comprising a tubular 60 cutter formed at its lower end with a cutting-edge, a handle secured to the upper end of said cutter, a cutter-ring of uniform width mounted in the tubular cutter upon a pivot extending transversely through the 65 cutter-ring, a transverse pin arranged for vertical movement in the handle, and a link connecting the said pin with the said cutter.

2. A grapefruit corer, comprising a tubular 70 cutter formed at its lower end with a cutting-edge, a handle secured to the upper end of said cutter, a cutter-ring mounted in the tubular cutter upon a pivot extending transversely through the cutter-ring, a transverse pin arranged for vertical movement 75 in the handle, a link connecting the said pin with the said cutter, and a spring tending to force the link downward.

3. A grapefruit corer, comprising a tubular 80 cutter formed at its lower end with a cutting-edge, a handle secured to the upper end of said cutter, a cutter-ring mounted in the tubular cutter upon a pivot extending transversely through the cutter-ring and provided with upper and lower cutting-edges, a 85 transverse pin arranged for vertical movement in the handle, and a link connecting the said pin with the said cutter.

4. A grapefruit corer, comprising, a tubular 90 cutter having a cutting-edge at its lower end, a sheet-metal handle secured to said cutter, said handle comprising a shank and a grip, said shank formed with vertical slots, a pin extending through said slots, finger-pieces mounted at opposite ends of said pin, 95 a cutter-ring mounted in the tubular cutter upon a pivot extending transversely through the cutter-ring, and a link connecting said pin with the cutter-ring.

5. A grapefruit corer, comprising a tubular 100 cutter having a cutting-edge at its lower end, a sheet-metal handle secured to said

cutter, said handle comprising a shank and a grip, said shank formed with vertical slots, a pin extending through said slots, the edges of the said shank turned inward above said pin and a spring within said shank and tending to force the pin downward, finger-pieces mounted on opposite ends of said pin, a

cutter-ring mounted in the tubular cutter upon a pivot extending transversely through the cutter-ring, and a link connecting said pin with the cutter-ring.

In testimony whereof, I have signed this specification.

WILLIAM E. WALSH.
